Inventor:

James H. Rand

by Robert Robert Cushman

Att'y:

UNITED STATES PATENT OFFICE

JAMES H. RAND, OF NORTH TONAWANDA, NEW YORK, ASSIGNOR, BY MESNE ASSIGNMENTS, TO REMINGTON RAND INC., OF NEW YORK, N. Y., A CORPORATION OF DELAWARE

INDEX DEVICE

Application filed May 24, 1924. Serial No. 715,612.

This invention relates to index cabinets having a plurality of superposed sections but more particularly to cabinets of that type in which there are sliding frames or shallow 5 drawers containing index elements and consists in the novel features hereinafter more fully described and particularly pointed out in the claims.

One preferred embodiment of the invention is illustrated in the accompanying drawings in which:

Fig. 1 is a fragmentary front elevation of the cabinet showing one of the frames or drawers suspended in depending position;

Fig. 2 is a transverse section taken on line 2—2 of Fig. 3;

Fig. 3 is a longitudinal section taken on the line 3—3 of Fig. 2; and

Fig. 4 is a fragmentary top plan view 20 partly in section of one of the drawers and corresponding section.

Referring to the drawings, the cabinet includes a top section 1, a bottom section 2 and two intermediate sections. The top section 1 comprises a body portion 3 upon the lateral 25 margins of which are welded or otherwise suitably secured the channel-shaped side walls 4. The upper end of the side walls 4 are bent inwardly to form flanges 5 which 30 extend parallel to the body portion 3 and the outer ends of the flanges 5 are bent downwardly at right-angles to form inner walls 6. The end walls 4' of the top section 1 are formed by bending the ends of the body portion 3 upwardly at right-angles thereto, thence inwardly to provide flanges 5', and thence downwardly to form inner walls 6'. Strips 7 are suitably fixed to the side walls 4 and are bent inwardly at 8 and downwardly 35 at 9 to fit within the flanges 5 and the inner walls 6, as shown in Fig. 2 and the lower ends of the strips 7 are bent inwardly to form supporting flanges 10 which extend parallel to the body portion 3.

45 A cover 11 is provided with depending

end walls 12 and side walls 13 and the side walls are bent inwardly at right-angles to form flanges 14 which rest against the supporting flanges 10 of the strips 7. The cover 11 is held within the top section 1 by the frictional engagement between the walls of the cover and the inner walls of the section. U-shaped strips 15 are suitably fixed to the end walls 4' and reinforce the ends of the top section 1 (Fig. 3). The 50 U-shaped strips 15 provide stress-reducing sections for the top section in order to distribute and equalize stresses thereon to prevent deformation of the section.

The bottom section 2 comprises a body 60 member 16 having side walls 17 which are suitably fixed to the under side of the body member. The side walls 17 are bent inwardly at right-angles to form flanges 18 (Fig. 2), and the flanges 18 are bent upwardly to provide inner walls 19 which extend parallel to the walls 17. The ends of the body member 16 are bent downwardly at right-angles to form integral end walls 20 and the end walls are bent inwardly to provide flanges 21. The flanges 21 are bent upwardly to form inner walls 22 extending parallel to the end walls 20.

The intermediate index receiving sections are substantially alike and each comprises a body portion 23 bent upwardly at opposite margins to form integral side walls 24. The side walls 24 are bent inwardly at right-angles to form flanges 25 for supporting the sides of the superposed sections of the cabinet. The supporting flanges 25 are bent downwardly to provide inner walls 26 extending parallel to the side walls 24. The rear end of the body portion 23 is bent upwardly to form an integral end wall 27 which 75 supports the inner ends of superposed cabinet sections. The forward end of the bottom member 23 is bent upwardly and inwardly to form a flange 28 providing a stop for a purpose hereinafter described.

In accordance with this invention means are provided to hold the various sections of the stack in proper relation to each other and securely fasten them together. It is preferable that individual means be provided for each section to enable the size of the stack to be increased or diminished without detaching all the sections from each other. Wire catches are employed in the form of spring arms 29 having Z-shaped hooks at one end and heads 30 at the other end. The hook end of each spring arm 29 is provided with a horizontal portion 31, a vertical portion 32, and a horizontal end portion 33. The catches are all similarly constructed with the exception of those within the top section 1 which are provided with a downwardly and outwardly bent head 30¹ to enable ready access to be obtained thereto after the cover 11 is removed.

The end portions 33 of the catches are first inserted into aligning holes 34 and 34' in the body portions of adjacent sections, and thereafter the catch is turned to force the right-angle portion 32 into the holes so that the portion 33 bears against one of the sections. The spring arm 29 may then be sprung into the channel formed between the inner and outer walls of the section, such as the channels defined by the walls 17 and 19, and the walls 24 and 26, shown in Fig. 2. Preferably four catches are employed for each section, there being two on either side of the section, although the number may be varied as desired. When it is desired to increase or diminish the size of the stack, the top section is first removed after the catches have been disengaged, and thereafter sections may be added or removed as desired.

Index supporting frames or drawers are slidable in the sections and each drawer comprises a bottom member 35 formed with integral side walls 36 and an integral front wall 37. An opening 38 is formed in the front wall 37 by flanging or bending the material inwardly to enable the drawers to be readily pulled out from the respective sections. A strip 39 is suitably fixed to the rear end of the base member 35 and is formed with a hooked end portion 40 which serves as an abutment to cooperate with the stop 28 on the intermediate sections, so that the drawers may be pulled out and suspended in a depending position, as shown in Fig. 1, thus presenting the index elements within the drawer in a convenient position for inspection or other use. Obviously the drawers may be withdrawn completely from the cabinet if desired by lifting their rear ends when almost extended to disengage the strip 39 from the stop 28.

The upper edges of the side wall 36 of the drawers are bent inwardly at right-angles to form flanges 41 to which L-shaped strips 42 are suitably fixed. A series of independent

index elements 43 in the form of cards are arranged within each of the drawers 35 and have overlapping margins 44 upon which suitable indicia may be inscribed. The index cards are secured within the frames in any suitable manner as for example by the rails 45 which are held between the strips 42 and the base member 35 which define therebetween channels upon opposite sides of the frame furnishing relatively narrow elongate guide slots for the ends of the index cards.

In order to hold the margins of the index cards in substantially the same longitudinal plane an inclined supporting plate 46 is formed with an integral depending flange 47 at one end thereof and the opposite end bears against the body portion 35 of the drawers. A depressed portion 48 of the supporting plate is conveniently connected to a struck portion 49 on the body member by a rivet 50. Owing to the inclination of the supporting plates 46 toward the inner end of the drawers the margins of the outer cards are held away from the bottom of the drawers thus presenting them in plain view for inspection, and also permitting more convenient handling thereof.

The forward edge of the plate 46 is cut away at 51 to permit one or more fingers to be inserted through the opening 38 in the drawer so that the drawers may be conveniently pulled out from their respective sections and also to enable the cards adjacent thereto to be readily grasped. The front wall of each frame may be provided with an index slip 52 in which is a slip 53 bearing any indicia indicative of the contents of the frame.

The construction of the cabinet enables it to be expanded to any reasonable extent by means of the spring catches and although it is preferable that the cabinet be constructed of sheet material, such as sheet metal, the invention is not restricted in any way to the employment of any particular material and in accordance with the material employed minor details of construction may be varied without departing from the spirit of the invention.

I claim:

1. An index device, comprising a cabinet having a plurality of superposed sections, one of said sections forming a top section, said top section being normally horizontally disposed and comprising a sheet metal body having side and end walls, laterally and inwardly extending flanges at the upper and lower edges of said walls, the upper flanges terminating in downwardly extending portions defining a cover receiving opening, and stress reducing members extending transversely of said body and embraced by said flanges and the downwardly extending portions.

2. An index device, comprising a cabinet having a plurality of superposed sections, one of said sections forming a top section,

said top section being normally horizontally disposed and comprising a sheet metal body having side and end walls, laterally and inwardly extending flanges at the upper and lower edges of said walls, the upper flanges terminating in downwardly extending portions defining a cover receiving opening, and U-shaped members extending transversely across the front and rear ends of said body 10 embraced by said flanges and retained by said downwardly extending portions.

Signed by me at Boston, Massachusetts,
this 16th day of May, 1924.

JAMES H. RAND.
